(57) **CLAIM**

The ornamental design for a landscape edging with integral illumination and irrigation means, as shown and described.

DESCRIPTION

FIG. 1 is a perspective view of a landscape edging with integral illumination and irrigation means, showing our new design;

FIG. 2 is a right view thereof, with a left view being a mirror image;

FIG. 3 is a front view thereof;

FIG. 4 is a rear view thereof;

FIG. 5 is a top view thereof; and,

FIG. 6 is a bottom view thereof.

The broken lines shown on the drawings depict environment only and form no part of the claimed design.
